(57) **CLAIM**

The ornamental design for a camera, as shown and described.

DESCRIPTION

FIG. 1 is a top, front and side perspective view of a camera showing my new design;

FIG. 2 is a front elevational view thereof;

FIG. 3 is rear elevational view thereof;

FIG. 4 is a top plan view thereof;

FIG. 5 is a side elevational view thereof from the right of FIG. 2; and,

FIG. 6 is a side elevational view thereof from the left of FIG. 2.

The portions of the camera in broken lines are shown for illustrative purposes only and form no part of the claimed design.
